FREDERICK N. ROSE, OF DETROIT, MICHIGAN, ASSIGNOR, BY MESNE ASSIGNMENTS, TO
BRIGGS MANUFACTURING COMPANY, OF DETROIT, MICHIGAN, A CORPORATION OF
MICHIGAN

COTTON BAT FEEDING MACHINE

Application filed October 6, 1930. Serial No. 488,807.

This invention relates to cushion forming mechanism and more particularly to cotton bat feeding mechanism for use in machines of this character.

5 While the structure forming the particular subject matter of this invention may be employed with facility in connection with various types of cushion sewing or upholstery forming mechanism, it finds particular utility 10 in connection with the general form and arrangement of cushion forming mechanism shown and described in my co-pending joint application, Serial No. 490,034.

15 It is one of the primary objects of this invention to provide a mechanism for supporting and continuously feeding a plurality of strips of cotton bat and for simultaneously presenting a plurality of strips of cotton bat in predetermined relation and association 20 with the finish and lining fabrics of the cushion to the sewing mechanism.

Another object of this invention is to simplify, render more efficient and improve generally structures of this character.

25 Another object of the invention is to provide mechanism of this character wherein the strips of cotton bat may be fed to the associated mechanism of the cushion forming machine in timed relation thereto and in such 30 a manner as to prevent a rupture or breaking of the strips due to the dragging or longitudinal tensioning of the strips.

The above and other objects, advantages 35 and novel details of construction of this invention will be made more apparent as this description proceeds, especially when considered in connection with the accompanying drawings, wherein

40 Figure 1 is a fragmentary side elevational view of a cushion or upholstery forming or sewing mechanism constructed in accordance with my invention with my improved cotton bat feeding mechanism associated therewith;

45 Figure 2 is a top plan view of the structure illustrated in Figure 1;

Figure 3 is a fragmentary vertical sectional view taken substantially on the line indicated by 3—3 in Figure 4;

50 Figure 4 is an enlarged fragmentary vertical sectional view taken substantially on

the plane indicated by line 4—4 in Figure 3;

Figure 5 is an enlarged fragmentary side elevational view of a portion of the machine showing more in detail the drive mechanism;

Figure 6 is an enlarged fragmentary horizontal sectional view taken substantially on the plane indicated by line 6—6 in Figure 1;

Figure 7 is a side elevational view of the structure illustrated in Figure 6;

Figure 8 is an enlarged vertical sectional view taken on the plane indicated by line 8—8 in Figure 1;

Figure 9 is an enlarged fragmentary vertical sectional view taken substantially on the plane indicated by line 9—9 in Figure 1;

Figure 10 is a fragmentary horizontal sectional view taken substantially on the plane indicated by line 10—10 in Figure 4, and

Figure 11 is a vertical fragmentary sectional view taken substantially on the plane indicated by line 11—11 in Figure 4.

Referring now more particularly to the drawings wherein like reference characters indicate like parts and more especially to Figures 1 and 5, it will be noted that there is 75 illustrated the adjacent end of the cushion sewing or forming mechanism which, as will appear more fully hereinafter, includes the finish and lining fabric forming mechanisms, the cotton bat breaker mechanism and the 80 sewing mechanism. This portion of the machine also includes a driving means for the several units of the machine including the driving means for the cotton bat feeding mechanism forming the particular subject of 85 this invention.

In the drawings the reference character 10 indicates the frame of the machine upon which, see particularly Figure 1, is mounted a motor 11 driving a pulley 12 with which 90 a belt 13 engages. This belt drives a pulley 14 mounted on a shaft 15 which extends into a housing or casing 16 within which is contained a standard type of reduction gearing (not shown). The live or driven shaft of this 95 reduction gearing is indicated by the reference character 17. A chain 18 driven directly by the shaft 15 drives through gearing 19 a sewing head or mechanism operating shaft 20. 100

The shaft 17 is provided beyond or inside the frame 10 with a sprocket wheel 21 with which a chain 22 engages, this chain passing around a sprocket wheel 23 keyed to a shaft 24 for driving the main conveyor of the machine. Arranged on shaft 17 exteriorly of the frame 10 is a sprocket wheel 25 with which a chain 26 engages. This chain passes around a plurality of driving sprockets which include 5 sprocket 27 keyed to shaft 28 for driving the front roll of the machine. The chain then passes around sprocket 29 keyed to the end of the lower cotton bat breaker shaft 30, this being the continuously driven shaft of the cotton breaker mechanism illustrated and described more fully in my co-pending application, Serial No. 461,556. The chain then passes around sprocket 31 which drives foundation forming mechanism shaft 32. From 10 sprocket 31 the chain passes around sprocket 33 keyed to shaft 34 employed for driving the cloth forming device. The chain 26 then passes around an idler sprocket 35 and thence back around sprocket 25.

25 As seen best in Figure 3, cotton bat breaker shaft 30 extends transversely of the machine being rotatably journaled in the frame 10. The other end of breaker shaft 30 is drivingly connected by means of gearing 36 to 30 the upper cotton bat breaker shaft 37 which is adapted to be intermittently operated, the driving connection 36 between the shafts being capable of automatic operation periodically for stopping the operation of shaft 37 35 for predetermined intervals. The means for effecting this intermittent operation of the upper breaker shaft 37 is illustrated and described in detail in my co-pending application, Serial No. 461,556.

40 Fixed to shaft 37 (see particularly Figure 3) is a sprocket wheel 38 with which a chain 39 engages. The two flights of this chain pass around idler sprockets 40 and 41 and one flight thereof passes around an adjustable idler sprocket 42 whereby the slack in chain 39 may be taken up.

45 The reference character 43 indicates a frame in the nature of a superstructure mounted upon frame 10 and rotatably journaled in this frame 43 at one side of the machine, is a shaft 44 having fixed thereto a sprocket 45 with which chain 39 engages. The other end of this shaft has fixed thereto 50 a gear 46 meshing with an idler gear 47 which in turn meshes with a gear 48 fixed to the end of cotton bat conveyor drive shaft 49. This shaft extends transversely of the machine as best illustrated in Figure 3 and is rotatably 55 journaled in the superstructure frame members 43. This shaft has keyed thereto a plurality of driving sprockets 50 arranged preferably adjacent the ends of this shaft. These sprockets drive the cotton bat conveyor indicated generally by the reference character 51

in a manner to be more fully hereinafter described.

The reference character 52 indicates a pair of uprights of a conveyor supporting structure and 53 a pair of shorter uprights connected to uprights 52 by horizontal frame members 54.

Vertically adjustably mounted on each upright 52 is a bearing support 55. Supported by each bracket or supporting member 55 is a plate 56 which in turn supports adjacent ends of track or guideways 57 and 58 for the upper and lower flights of the conveyor chains yet to be referred to. Extending transversely of the machine and supported by the brackets 55 is a shaft 59 carrying idler sprockets 60 for the chains 61 of the conveyor belt 51. Other idlers 62 are mounted on the brackets 55 for the lower flight of the conveyor belt. The ends of shaft 59 are rotatably journaled in bearings 63 fixed to the supporting brackets 55 whereas the stub shafts 64 supporting the idler sprocket 62 are adjustably mounted upon their respective brackets 55 by pin and slot connections 65, see particularly Figure 1. Thus, the slack in the lower flight of the belt may be taken up. Suspended below the bracket 55 is a roller 66 over which the sheet of lining or foundation fabric L passes. This roller 66 is supported at its ends respectively by brackets 67 adjustably connected by pin and slot connection 68 with the bracket 55. A considerable part of this structure is shown in detail in Figure 8.

The forward end of the conveyor belt 51 passes around the sprockets 50 mounted on shaft 49 supported in the frame members 43. Supporting gears 69 are provided in the frame members 43 connected by transversely extending cross rods 70. Mounted on each of these cross rods is a plate member 71 which provides supports for the forward ends of track-ways 72 and 73 in the form of bars upon which the chain 61 of the belt-like conveyor 51 slide. The track-ways 72 and 73 support the upper and lower flights of the conveyor respectively. The rear end of these track-ways 72 and 73 are supported by a similar plate 74 supported in turn on a transverse rod 75 corresponding to rod 70 and supported by ears 76 carried by brackets 55. The ends of the track-ways 73 supported by the plate 74 are adjustably connected thereto by means of pin and slot connection 77.

The right hand ends of track-ways 57 and 58 as viewed in Figure 1 are supported by bracket plates 78.

Mounted on the top of uprights 53 are bearing blocks 79 rotatably supporting a transverse extending shaft 80 to which are keyed sprockets 81 for engaging the sprocket chain 61 of the conveyor belt. From the heretofore described construction it will be apparent that the endless belt-like conveyor 51 is driven from its forward end through shaft 49

and sprockets 50, the conveyor partaking during approximately half of its length of a substantially horizontal flight and during the other half of its length of an inclined flight. 5 The inclined portion extends in a downward direction and terminates substantially intermediate of a vertical cotton bat roll supporting frame or cotton reel, indicated generally by the reference character 82. On this frame, 10 in a manner to be more fully hereinafter referred to, a plurality of rolls of cotton bat are adapted to be supported, these rolls constituting the cotton bat supply for the strips fed to the cushion forming mechanism by the 15 feeding means being herein described.

While obviously the roll supporting frame may be of any desired construction, it preferably consists of a plurality of transversely and longitudinally spaced uprights 83 upon 20 which are mounted a plurality of horizontally arranged cotton reel brackets 84. These brackets 84 are arranged in vertically spaced tiers, horizontally aligned extending longitudinally of the cotton reel frame 82 as will 25 be most fully understood by comparison of Figures 1 and 2. Each horizontal tier comprises a plurality of longitudinally extending roll shafts 85, herein shown as four in number, each shaft having fixed thereto a 30 plurality of rolls 86, there being three longitudinally spaced sets of rolls 86 as seen most clearly in Figure 2. The axes of the shafts 85 are arranged on a substantially semi-circular member so that the periphery 35 of the rolls mounted thereon provide a substantial cradle in which the roll of cotton bat indicated as B, may rest. The rolls 86 are all driven simultaneously at the same speed and in the same direction and for this 40 purpose the corresponding ends of all of the shafts 85 of each horizontal tier are provided with pinions 87 adapted to mesh with intermediately arranged idlers 88. Shaft 85', this being the shaft to the left of the lowermost 45 tier, is extended and has keyed thereto a gear 89 meshing with an idler gear 90 which in turn meshes with a gear 91 on a shaft 92. This shaft, (see particularly Figure 2) is provided with a sprocket wheel 93 with 50 which a sprocket chain 94 engages, this chain engaging a sprocket 95 on the end of shaft 80, (see particularly Figure 2).

In the structure thus far described, all of the rolls of the lowermost tier will be 55 driven in synchronism as will be apparent. The rolls of the tier next above may be driv- 60 ingly connected to the lowermost tier of rolls by extending one of the shafts 85 and fixing thereto a sprocket wheel 96 with which a sprocket chain 97 engages, this sprocket chain engaging a sprocket wheel 98 fixed to one of the shafts 85 of the tier arranged im- 65 mediately above. In a similar manner the other tiers of rolls are each driven from the 70 tier arranged immediately therebeneath, so

that all of the rolls are simultaneously driv- 75 en at the same uniform speed and in the same direction, so that the rolls of cotton bat B supported thereon may be rotated in a direct timing to unwind the same.

Due to the unwinding action of the rolls of cotton bat B, the cotton bat is fed to the upholstery forming mechanism or toward the left, in Figures 1 and 2 without longitudinally tensioning the cotton bat strips. 75 A plurality of supporting or guiding chutes 100 are provided, one for each roll of cotton bat, these chutes consisting of shallow pan-like members of a width equal to the width of the cotton bat roll at one end, and con- 80 verging toward the other end, each into a reduced end 101 substantially the width of the cotton bat strip. The discharge ends of these chutes are also supported and positioned as to discharge the cotton bat strips 85 upon the upwardly inclined portion of the conveyor belt 51 which in turn conveys the cotton bat strips, also without imparting longitudinal tension thereto, toward the up- 90 holstery forming mechanism.

The bat strips after leaving the conveyor 95 51 pass downwardly over a roll 102 and into guide tubes 103, see Figures 4, 10 and 11. There is a guide tube 103 provided for each cotton bat strip as will be apparent, these 100 tubes acting to accurately guide and locate the bat strips with respect to the cotton bat feeding means which in turn introduces the bat strips into the tubes or plaits of the up- 105 holstery as the same are produced.

As will be seen from Figures 10 and 11, the 110 guide tubes 103 are arranged preferably in two parallel rows, the tubes of each row being staggered with respect to the tubes of the other row so that the proper longitudinal spacing may be accomplished. To removably and adjustably support the guide tubes 103, I provide a transversely extending supporting rod or member 104 mounted upon suitable brackets 105 at opposite sides of the machine. Each guide tube 103 is provided with an angularly extending bracket 106 having a hook-shaped end 107 adapted to engage the support 104 between spaced collars 108. With this construction, the guide tubes 103 115 may be properly spaced transversely of the machine as will be obvious and may be removed when access to parts below these tubes becomes necessary. As seen most clearly from Figure 4, the cotton bat strips B pass downwardly through the guide tubes 103 and are engaged by the cotton bat feeding rolls 109. By means of these rolls the cotton bat is forcibly fed to the upholstery forming mecha- 120 nism and by suitably operating these feeding rolls, as more fully described in copending application, Serial No. 461,556 the cotton bat is periodically severed or broken for reasons which appear more fully in the said copending application. 125

As seen in Figure 4, the finish or top fabric F of the cushion or upholstery is presented to the upholstery forming mechanism by means of the main conveyor 110 and the cotton bat strips B are deposited thereon. The bottom or lining fabric L is presented by forming mechanism indicated generally by the reference character 111 and deposited on top of the cotton bat strips B and the finish or top fabric F. The reference character 112 indicates generally the sewing mechanism by means of which the finish fabric F and lining fabric L are united to produce longitudinal plaits or tubes. The completed upholstery after leaving the sewing mechanism 112 passes around roll 113 and is conducted away.

It will be understood that the rolls B of cotton bat are deposited upon the cradles formed by the sets of rolls 86 which sets of 20 rollers peripherally engage the cotton bat rolls and upon being rotated, unreel the bat rolls by reason of their frictional contact therewith.

By reference to Figures 1, 2, 6 and 7, it will be noted that there are provided longitudinal guides 115 with which the spindles 116 of the bat rolls engage. These vertical guides prevent the lateral displacement of the bat rolls during the unreeling thereof but permit 30 the vertical displacement thereof due to the decreasing size of the bat rolls as they are unreled. It is obvious that with this construction the bat rolls which are rather large and cumbersome may be quickly and conveniently placed or stacked in the unreeling frame.

From the foregoing description it will be apparent that I have provided means whereby the necessary number of rolls of cotton bat 40 may be supported and the strips of cotton bat B from all of the rolls simultaneously fed to the upholstery forming mechanism without imparting longitudinal strain to the bat strips. This enables the use of ordinary cotton bat strips, thus making it unnecessary to use cotton bat strips provided with internally arranged longitudinal reinforcing or strengthening means as has been customary in machines of this general character here- 45 tofore employed. Moreover, in view of the fact that the feed of the bat strips is timed with respect to the rest of the mechanism, each strip of cotton bat will be presented to the forming mechanism without being longitudinally stretched or compressed, therefore 55 enabling the production of tubular upholstery of remarkable uniformity.

While the embodiment of this invention herein specifically illustrated and described 60 has been found in practice to give good results, nevertheless it will be apparent to those skilled in this art that many changes and rearrangements of all of the non-essential details of construction may be resorted to without departing from the spirit and scope of

the invention and to this end reservation is made to make such changes as may come without the purview of the accompanying claims.

What I claim as my invention is:

1. Cotton bat feeding means for use in combination with upholstery forming machines and the like comprising a plurality of sets of rollers forming cradles to peripherally support rolls of cotton bat, means for 70 rotating said rollers to rotate said cotton bat rolls in a direction to unreel the same, a conveyor driven in timed relation with said rollers and guiding chutes for conducting the unwound strips from each roll to said conveyor whereby the strips of cotton bat will be bodily presented to the upholstery forming mechanism without longitudinally tensioning said strips.

2. In upholstery forming mechanism, the combination with means for presenting strips of cotton bat between finish and lining fabrics, of feeding means for said cotton bat including, a roll supporting frame, longitudinally and vertically spaced sets of rollers mounted on said frame, each set of rollers being arranged to form a roll supporting cradle to receive and support a roll of cotton bat by engagement with a portion of its periphery, means for interconnecting the 90 rolls of each set and each set of rolls with one another, and means for driving said rollers to unreel said rolls of cotton bat.

3. In upholstery forming mechanism, the combination with means for presenting strips of cotton bat between finish and lining fabrics, of feeding means for said cotton bat including, a roll supporting frame, longitudinally and vertically spaced sets of rollers mounted on said frame, each set of rollers being arranged to form a roll supporting cradle to receive and support a roll of cotton bat by engagement with a portion of its periphery, means for interconnecting the 100 rolls of each set and each set of rolls with one another, and means for driving said rollers to unreel said rolls of cotton bat, an endless conveyor and means for depositing the unwound strips from said rolls on to said conveyor.

4. In upholstery forming mechanism, the combination with means for presenting strips of cotton bat between finish and lining fabrics, of feeding means for said cotton bat including, a roll supporting frame, longitudinally and vertically spaced sets of rollers mounted on said frame, each set of rollers being arranged to form a roll supporting cradle to receive and support a roll of cotton bat by engagement with a portion of its periphery, means for interconnecting the 110 rolls of each set and each set of rolls with one another, means for driving said rollers to unreel said rolls of cotton bat, and endless conveyor and means for depositing the un- 120

wound strips from said rolls on to said conveyor, and means for driving said conveyor in timed relation with said rollers.

5. In upholstery forming mechanism in which strips of cotton bat are presented to the sewing mechanism between sheets of finish and lining fabrics, means for feeding the cotton bat including a cotton bat roll supporting frame, a plurality of sets of rollers journaled on said frame, each set of rollers having their axes arranged in a substantially semi-circular plane to provide a roll supporting cradle adapted to peripherally engage a roll of cotton bat, means associated with each set of rollers for engagement with the spindle of each roll to prevent lateral while permitting vertical movement of said roll, and means for driving the rollers of each set, for the purpose set forth.

20. In mechanism of the class described, cotton bat feeding means including, a frame, a plurality of sets of rollers, each set of rollers being arranged to provide a cradle adapted to peripherally engage and support a roll of cotton bat, means engaging the spindle of each roll to prevent its displacement from said cradle upon being unreeled, an endless conveyor, guiding chutes associated with each set of rollers for guiding the unreeled strip of cotton bat and depositing the same on to said conveyor, and means for actuating said endless conveyor and said rollers in timed relation, as and for the purpose set forth.

35. 7. In upholstery forming mechanism, cotton bat feeding means including, a frame, a plurality of sets of rollers journaled on said frame, said sets of rollers being arranged in longitudinally spaced superposed rows, the 40 rollers of each set being journaled so as to cooperate to form a cradle which supports a roll of cotton bat by engaging a portion of its periphery, gearing interconnecting the rollers of each set so that they may be simultaneously driven in the same direction, the 45 rotation of the rollers of each set acting by frictional engagement with said cotton bat roll to unreel the same, means interconnecting each set of rollers so that they may be simultaneously rotated, an endless conveyor 50 upon which the unreeled strips of cotton bat are deposited, a guide chute associated with each set of rollers for directing the strip of cotton bat on to said conveyor and means 55 driving said conveyor in timed relation to said sets of rollers.

In testimony whereof I affix my signature.
FREDERICK N. ROSS.
